UNITED STATES PATENT OFFICE

JESSUP SALISBURY, OF HAMDEN, CONNECTICUT, ASSIGNOR TO THE AMERICAN BUCKLE COMPANY, OF WEST HAVEN, CONNECTICUT, A CORPORATION OF CONNECTICUT

PRONG BUCKLE

Application filed June 28, 1929. Serial No. 374,392.

This invention relates to prong buckles having means for protecting the prong points, the buckle being employed for adjusting the length of straps and maintaining 5 the adjusted length by penetrating the strap material.

The objects of the invention are to provide a buckle of which the prong member is made to relatively slide upon the frame member; 10 to provide such a buckle with means for protecting the prong points; and to provide means for locking the relatively sliding members in a prong protecting position.

The invention consists in the novel constructions, to be hereinafter described or claimed, for carrying out the above stated objects and such other objects as may herein-after appear.

The character of the invention may be best 20 understood by reference to one illustrative device embodying the invention and illustrated by the several figures in the accompanying drawing in which the Figure 1 is an elevation of the buckle with protected 25 prong points; the Figure 2 is a similar elevation, but with prong points visible; and the Figure 3 is a section on the line 3—3 of the Figure 1.

The invention is not limited to any specific 30 form of construction and the details of the device may be varied to produce the novel features hereinafter claimed, the device as illustrated, however, is a buckle comprising the frame member 1 and the prong member 35 2 assembled for relatively sliding with means provided for the protection of the prong points. The two members of the buckle are each preferably formed of resilient wire. A middle portion of the wire of which the frame 40 member is constructed is flattened in the plane of the frame substantially throughout such middle portion, the flattened portion 3 being bent to form the spaced arched sections 4, the remaining end portions of the wire 45 being bent to provide the two side arms 5 of the frame member, the wire extremities being bent inwardly in parallel relation to the portion 3 and providing looped ends 6, each snugly positioned against its respective side 50 arm 5. A middle portion of the wire of

which the prong member 2 is constructed is bent to form the loop 7 having the lower bar 8 and the bar portions 9 turned back in the plane of the loop and bent away from the loop to provide the side arms 10 which are 55 off-set inwardly to provide the spaced prongs 11. Depressions 12 are provided in the inner surface of each of the side arms 10. The two members of the device are assembled by means of the looped ends 6 of the frame member being looped around the side arms 10 of the prong member in such manner that the side arms 10 are held outwardly under lateral tension so that, when the relatively sliding members are in the position illustrated by 60 the Figures 1 and 3 the side constructions, of which the side arms 10 are parts, spring inwardly by reason of depressed portions of the arms 10 sliding within the loops 6 of the side arms 5 of the frame member, thus locking 65 the members in such position wherein the prong points 11A are protected within the spaced arched sections 4. When the relative sliding members are moved to the position illustrated by the Figure 2 the prong points 70 11A are withdrawn from their protecting arched coverings and the side constructions of the prong member are held under increased lateral tension by reason of the full formation 75 of the side arms 10 sliding within the loops 6. The prong points 11A are made outwardly eccentric, as regards the axis of each prong, so that they penetrate the strap material at relative points farther apart to adapt 80 the strap to co-operate with the released tension upon the side constructions of the prong member as the relatively sliding members reach the locked position and the strap punctures are centered upon the prongs. The buckle is manually operated from one position 85 to the other.

I claim:

1. A prong buckle comprising a prong member; prongs provided by, and substantially 95 lying in the plane of, the member; a prong point provided by each prong, the point being eccentric to the axis of the prong; a frame member, the members being assembled for a limited relative sliding movement; and means 100

provided by the frame member for protecting the prong points.

2. A prong buckle comprising a prong member; prongs provided by, and substantially lying in the plane of, the members; a frame member, the members being assembled for a limited relative sliding movement; and means carried by the frame for protecting the prong points, said means comprising a flattened portion of the frame member, the flat portion being bent to form arched sections thereof registering with and admitting the prong points thereunder.

3. A prong buckle comprising a prong member having parallel arms; prongs provided by, and substantially lying in the plane of, the member; a depression provided by an inner facing portion of each arm; a frame member normally mounted upon the depressed portions of the arms for a limited relative sliding movement only by outwardly tensioning the arms; and means carried by the frame member for protecting the prong points, said means comprising a flattened portion of the frame member, the flat portion being bent to form spaced arched sections thereof registering with and admitting the prong points.

JESSUP SALISBURY.
